Primary Examiner — Susan Bennett Hattan*Assistant Examiner* — Marie Fast Horse(74) *Attorney, Agent, or Firm* — Dennis L. Thomte; Thomte Patent Law Office LLC(57) **CLAIM**

The ornamental design for an air blower device, as shown and described.

DESCRIPTION

FIG. 1 is a perspective view of the air blower device of this invention;

FIG. 2 is a top view of the air blower device of this invention;

FIG. 3 is a forward end view of the air blower device of this invention;

FIG. 4 is a side view of the air blower device of this invention;

FIG. 5 is a rearward view of the air blower device of this invention;

FIG. 6 is a side view of the air blower device of this invention; and,

FIG. 7 is a bottom view of the air blower device of this invention.

The broken lines in FIGS. 6 and 7 depict parts of the air blower device that form no part of the claimed design.

1 Claim, 3 Drawing Sheets(56)
